UNITED STATES PATENT OFFICE

2,679,387

CARBURETOR

Enoch Rector, New York, N. Y.

Application January 8, 1952, Serial No. 265,421

10 Claims. (Cl. 261—51)

1

This invention relates in general to a carburetor of the vacuum air lift type, and has especial reference to improved means for the control of fuel, vapor or air to the mixing chamber of the carburetor.

The air lift feature disclosed in my abandoned application, Serial No. 66,047, filed December 18, 1948, consists in introducing air into the liquid fuel feed pipe, as near as practicable above the level of the fuel in the supply tank so as to mix with the air for the purpose of delivering fuel to the carburetor.

It is therefore an object of the present invention to eliminate the fuel pump and its accessories found to be faulty and requiring repair and replacement from time to time in connection with a carburetor for an internal combustion engine.

Another object of this invention is the provision of a reserve tank constituting a part of the carburetor of the indicated character, in which tank, the air and all fuel vapors are separated from the liquid fuel at the top of the tank and are delivered to the top of a float operated fuel admission valve member while the liquid fuel is delivered from the bottom of the tank into the float chamber. This provides a balanced fuel admission valve means readily responsive for idling and for all running speeds of the engine and vehicle.

Another object of the invention is the provision of a fuel reserve tank of the character mentioned so as to provide a fuel supply above the fuel level in the float chamber, in extreme cases, when the throttle valve is wide open or nearly so, and the engine speed is very slow and the intake manifold vacuum is not sufficient to draw the fuel from the reserve tank. However, this condition occurs only momentarily, and as soon as the engine speed is increased to 800 revolutions, the vacuum will be sufficient to draw fuel from the supply tank to refill the reserve tank to its normal capacity. Also the reserve tank eliminates all possibility of a "vapor lock" which occurs during very hot weather in all of the standard carburetors.

With the foregoing, other objects and advantages of the invention will appear when the following specification is read in conjunction with the accompanying drawings, in which:

Fig. 1 is a vertical sectional view, the section being taken substantially as indicated by the line 1—1 of Fig. 2, and certain parts being shown in side elevation.

Fig. 2 is a horizontal sectional view taken substantially on the line 2—2 of Fig. 1.

2

Referring now more particularly to the drawings, it will be apparent there is shown a hollow body or bowl 10 with a lateral extension 11 providing a circular liquid fuel chamber 12 and space 13 in communication therewith. The bowl 10 has a removable domed top cover 14 and a flanged base 15.

Centrally of the bowl 10 is a venturi 16 composed of sections fitting in the lower end of a tube 17 forming a main down draft passage 18 and a mixing chamber in conjunction with the base 15. It is to be understood that the upper end of the tube 17 will have suitable air intake and that the base 15 will be secured to the engine intake manifold in communication therewith.

The venturi has a plurality of passages or jets 19 which open into the passage 18 and also communicate with an annular space 20 which 20 communicates with a passage 21 in the bottom of the bowl extension 11.

A metering pin 22 is slidable up and down in a tubular guide 23. The lower end of the guide 23 has ports 24 and a plug 25. The ports 24 communicate with the interior of the guide. The plug 25 has an outlet port 26 and a stud 27. The extension 11 and base 15 are machined to receive the plug so that the port 26 establishes communication between the interior of the guide 23 and the passage 21. The upper end of the guide 23 is threaded in the cover 14 and its outer upper extremity has a packing unit 28 which receives the pin 22. The upper end of the pin 22 is operatively connected with the throttle valve operating means 29 which latter is also connected with a dash pot or pump 30 communicating with the chamber 12. The pin 22 cooperates with the port 26 to control the flow of gasoline from the chamber 12 to the spray jets 19 by way of the ports 24, and 26, passage 21 and space 20 in the order named.

An annular float 31 is arranged in the chamber 12. The float has a lever 32 which is fulcrumed on the extension 11, as at 33. The lever 32 has a rounded portion 34 disposed between parallel flanges 35 on the stem 36 of a conical valve member 37 on the lower extremity of the stem. A duct or passage 38 extends longitudinally through the stem and its valve member. The valve member 37 cooperates with a seat 39 carried by a tubular guide 40 held in place by a hollow threaded plug 41 and a bushing 42. The plug 41 extends upwardly through the base 15 and the bottom of the extension 11 in threaded engagement with said bottom and the lower tapped end of the guide 40. The bushing 42 is in

threaded engagement with the reduced screw portion 43 of the guide. There are ports 44 in the guide 40 above the seat 39. These ports 44 establish communication between the space 13 of the float chamber 12 and a passage 45 formed by the lower end portion of the guide 40 and the plug 41.

The valve member 37 with its stem 36 is balanced by pressure on its opposite ends, with the result that the varying vacuum pressure in the chamber 12 does not affect the fuel discharge, and a constant level of the fuel in the chamber 12 is maintained. The stem is machined a few thousandths of an inch smaller than the interior diameter of the guide 40 so that some air and gas vapor may leak through the guide 40 into the float chamber 12 as will more clearly appear hereinafter. Since there is no close tolerance fit of the stem 36 in the guide 40, the stem will not stick, but will be readily responsive to the movement of the float 31 in its control of the flow of fuel into the chamber 12 from the passage 45.

In accordance with another important feature of this invention, use is made of a fuel reserve vessel or tank 49 as a part of the carburetor. The tank 49 comprises a cylindrical side wall 50, a bottom 51 and a top 52. The bottom 51 has a lateral extension 53 to provide an outlet passage 54 for the tank in continuation with the passage 45, it being apparent that the plug 41 projects upwardly through the extension 53. The top 52 has a lateral extension 55 to provide an air and gas outlet passage 56. A hollow plug 57 is threaded in a tapped hole in the extension 55 and is connected by a union 58 to the upper end of the guide 40. The plug 57 has ports 59 which communicate with the hollow 60 of the plug thereby providing a passage which establishes communication between the passages 38 and 56. Thus the interior of the tank has a continuous flow passage from the top to the bottom thereof.

A liquid fuel feed or inlet pipe 61 from a main supply tank (not shown) is connected with the bottom 51. A riser tube 62 has its lower end screwed into a boss on the bottom 51 in communication with the pipe 61. The upper end of the tube 62 has a depending circular flange 63 and a coaxial vent 64 above the flange. Ports 65 and 66 in the tube 62 and flange 63 respectively, establish communication between the interior of the tank 49 and the interior of the tube 62 and the vent 64. Filtering screens 67 and 68 in spaced relation to each other engage circular shoulders 69 and 70 respectively, on a depending circular flange 71 formed on the top 52 at the inside thereof. A helical spring 72 surrounds the tube 62 between collars 73 and 74 on the tube 62 the latter having a shoulder for the collar 73. Each screen is of two semi-circular parts. The discharge ports 65 and 66 occur between the screens. A nut 75 screwed on the outer end of the vent 64 and bearing on the extension 55 helps to hold the top in place.

Liquid fuel and air lifted from the main supply tank flow upwardly through the pipe 61, tube 62 and ports 65 and 66 into the tank 49. It is to be understood that the liquid fuel is lifted from the supply tank into the reserve tank 49 through pipes 61 and tube 62, by suction action induced within the tank 49 at the top thereof, and by reason of the fact that liquid flows from a lower level of a higher pressure in the supply tank to a higher level of a lower pressure in the reserve

tank 49. The fuel in the tank 49 rises therein above the fuel level in the chamber 12. Thus a reserve supply of fuel is provided when, in extreme cases, the throttle valve is wide open or nearly so, and the engine speed is very low and the manifold vacuum is not sufficient to draw the fuel from the main supply tank. However, this condition occurs only momentarily. As soon as the engine speed increases to about 800 revolutions, the vacuum will be sufficient to draw fuel again and will refill the tank 49 to its normal capacity.

The air and gaseous fuel in the tank 49 above the level of the liquid fuel therein eliminates "air lock." The air and gaseous fuel always present at the top of the tank 49 are drawn through the path formed by the passage 56, ports 59, hollow 60, passage 38, ports 44 into the top of the chamber 12 when the valve member 37 is open. This gaseous fuel is drawn into the main air passage 18 through jets in tube 17 above the venturi 16. Also some of this vapor may pass between the stem 36 and the guide 40 to the ports 44 just prior to the opening movement of the valve member 37. Thereafter, liquid fuel flows from the bottom of the chamber 12 to passage 18 while liquid fuel is fed into chamber 12 from the bottom of the reserve tank 49 through the inter-communicating passages 54 and 45 and ports 44.

The present invention is not restricted to the details above described, but includes all constructions and modifications coming within the scope of the appended claims.

I claim:

1. A carburetor of the vacuum air lift type having the combination of a body providing a float chamber adapted to contain liquid fuel, said body also providing a main air intake passage communicating with said float chamber, a fuel reserve tank having a fuel and air inlet means extending from the bottom to near the top, an air and gas outlet passage at the top of the tank communicating with said float chamber, and a fuel outlet passage at the bottom of the tank, a seat on said body surrounding the fuel outlet passage, a valve member having a stem mounted on said body for up and down movement between an open and closed position with respect to said seat, said stem having a passage communicating at its opposite ends with said outlet passages, said valve member controlling the admission of fuel into said float chamber from said fuel outlet passage and the amount of vacuum in said tank by reason of said air and gas outlet passage, a float in said chamber responsive to the rise and fall of fuel in said chamber, and cooperative means on the stem and float by which the float moves the valve member for the stated purpose.

2. A carburetor as set forth in claim 1, and a throttle operated valve to control the flow of fuel through an outlet passage leading from the float chamber to a mixing chamber.

3. A carburetor as set forth in claim 1, wherein said valve member is balanced by pressure on one end of the stem and one face of the valve member.

4. A carburetor as set forth in claim 1, wherein said stem is slidable in a guide tube fixed on said body, and by reason of a difference in the cross-sectional size of said stem and guide tube enabling air and gaseous fuel to pass between the stem and the guide tube into said float chamber.

5. A carburetor as set forth in claim 1, wherein said fuel and air inlet means includes a riser tube extending from the bottom of the tank to

near the top thereof, and the upper end of the tube has discharge ports therein.

6. A carburetor of the vacuum air lift type having the combination of a fuel reserve container, a body providing a float chamber adapted to contain liquid fuel, said body also providing a main air intake passage communicating with said float chamber, a float in said chamber and having a lever fulcrumed on said body, an outlet passage leading from the interior of the container at the bottom thereof to the interior of said float chamber, valve means on said body operated by the lever of said float to control the flow of fluid through said passage to said chamber from said container and the amount of vacuum in said container, said valve means including a valve member having a stem, and intercommunicating passages leading from the top of said container into said valve member and its float chamber through said stem.

7. A carburetor of the vacuum air lift type having the combination of a body providing a float chamber adapted to contain liquid fuel, said body also providing a main air intake passage communicating with said float chamber, a fuel reserve tank, a liquid fuel and air inlet tube extending upwardly through the bottom of the tank to near the top of the tank, there being discharge ports in the upper end of the tube, said tank having an air and gas outlet passage leading from the top and a fuel outlet passage leading from the bottom, a seat on said body surrounding said fuel outlet passage, a valve member having a stem mounted on said body for up and down movement between an open and closed position with respect to said seat, said stem having a passage communicating at its opposite ends with said outlet passages, said valve member controlling the admission of fuel into said float chamber from said fuel outlet passage and the amount of vacuum in said tank, a float in said chamber responsive to the rise and fall of fuel in said chamber, and cooperative means on the stem and float by which the float moves the valve member for the stated purpose.

8. A carburetor as set forth in claim 7, wherein the ports of the inlet tube are so disposed within said tank that the level of the fuel in the tank will be above the level of the fuel in the float chamber.

9. A carburetor of the vacuum air lift type having the combination of a reserve fuel container, a body providing a float chamber and a main air intake passage communicating with said float chamber, said container having an outlet passage leading from its interior at the top and an outlet passage leading from its interior at the bottom thereof, and float operated valve means including a valve member having a duct extending longitudinally therethrough responsive to the rise and fall of fuel in the float chamber to establish communication of said passages and the float chamber and also for disestablishing the aforesaid communication.
10. A carburetor of the vacuum air lift type having the combination of a reserve fuel container, a body providing a float chamber and a main air intake passage communicating with said float chamber, said container having an outlet passage leading from its interior at the top and an outlet passage leading from its interior at the bottom thereof, and float operated valve means responsive to the rise and fall of fuel in the float chamber to establish communication of said outlet passages with said float chamber and also for disestablishing the aforesaid communication, said valve means including a slideable valve member with a stem having a duct extending through the valve member and the stem, the opposite ends of said duct being in communication with said outlet passages respectively, when the valve means is closed, and the opposite ends of said duct being in communication with said top outlet passage and the float chamber respectively, when the valve means is open.
